UNITED STATES PATENT OFFICE.

WILLIAM E. ANDRÉE, OF CHICAGO, ILLINOIS, ASSIGNOR TO NELSON & KREUTER COMPANY, A CORPORATION OF ILLINOIS.

IRONING-MACHINE.

No. 825,441.

Specification of Letters Patent.

Patented July 10, 1906.

Application filed November 2, 1905. Serial No. 285,695.

To all whom it may concern:

Be it known that I, WILLIAM E. ANDRÉE, a citizen of the United States, and a resident of Chicago, county of Cook, and State of Illinois, have invented certain new and useful Improvements in Ironing-Machines, of which the following is a specification and which are illustrated in the accompanying drawings, forming a part thereof.

10 This invention relates to machines especially adapted for the ironing of shirt-bosoms of the type shown in my pending application, Serial No. 262,562, filed May 27, 1905.

15 The object of the invention is to provide in a machine of this kind having a rocking ironing-tool means for applying uniform pressure of the tool on the work throughout its rocking movement. In machines of this kind the pressure is applied through the medium of a 20 spring; and the invention consists in so organizing the machine that the abutments between which the spring reacts are maintained at a substantially uniform distance apart throughout the entire rocking movement of 25 the ironing-tool. As shown in the accompanying drawings, pressure is applied to the ironing-tool by means of a coil-spring reacting between the abutments carried by the tool and an abutment carried by an oscillating 30 head, means being provided for oscillating this head in unison with the tool, thereby raising and lowering its abutment with the abutment carried by the tool.

35 The invention is illustrated in the accompanying drawings, in which—

Figure 1 shows a detail of the ironing-machine partly in elevation and partly in section, the ironing-tool being shown in its middle position in solid lines and in its two extreme positions in dotted lines. Fig. 2 is a 40 detail bottom plan section on the line 2 2 of Fig. 1. Fig. 3 is a detail of the oscillating abutment and the rod and spring for connecting it with the ironing-tool, and Fig. 4 is a 45 detail of certain parts employed in the machine for transmitting motion from the ironing-tool to the oscillating abutment.

One of the standards of the machine is shown at 10, its lower cross-beam at 11, and 50 its upper cross-beam at 12. A collar 13 is mounted to turn about the standard 10 and carries one or more arms 14, upon each of which is mounted the ironing-table 15. A vertical thrust-bar 16 is mounted so as to

slide through the cross-bar 11 and carries a 55 head 17 for engaging the base 18 of the ironing-table in order to raise the latter to the ironing plane.

Any suitable power mechanism may be applied to lift the rod 16. As shown, such 60 means comprise a steam-cylinder 19 and a piston 20, working therein and attached to the bar 16, means (not shown) being provided for supplying steam to and exhausting it from the cylinder.

65 The ironing-tool 21 will, as is usual in machines of this kind, be provided with means, (not shown,) such as steam-pipes, whereby it may be heated, and it is provided with a convex face and so mounted that this face will 70 rock upon the work when the latter is supported on the table 15, and the table is elevated to the position shown in Fig. 1. The ironing-tool is supported by means of a rod 22, pivotally attached to the tool at 23 and 75 passing upwardly and slidably through a sleeve 24, carried by an oscillating head 25, a nut 26 being fixed upon the upper end of the rod 22. The head 25 is housed within the upper cross-beam 12 of the machine and is 80 pivoted to the side walls thereof, as shown at 27. The head 25 is hollow, being formed of a pair of plates 28 29, united by a cross member 30. The sleeve 24 fits loosely between the plates 28 29 and is provided with trunnions 31, journaled in suitable boxes 32, provided at the bottom of the plates 28 29.

85 An actuating-bar 33 is secured by bolts to the ironing-tool 21 at 34 35 and projects into the standard 10, which is hollow, and is connected, by means of a pitman 36, with any suitable actuating mechanism, such as the crank-arm 37, carried by a shaft 38, rotated by means of a power-shaft 39, and intermeshing gears 40 and 41, carried by the two shafts. 90 The reciprocation of the pitman 36 will cause the ironing-tool 21 to rock on the table 15 between the dotted-line positions X Y. The rod 22 being attached to the center of the ironing-tool is necessarily given a vertical 95 movement as the plate rocks.

An expansion-spring 42 is coiled about the rod 22 and reacts between the lower end of the sleeve 24 and a knuckle 43, by means of which the rod is attached to the ironing-tool. 100 The office of this spring is to hold the ironing-tool forcibly against the work on the table 15, and it is obvious that as the tool ap-

proaches either of the extreme positions the spring must yield, and hence increase the pressure unless provision is made for raising the abutment against which its upper end is seated. Such provision is made by giving the head 25 an oscillating movement in unison with the rocking movement of the ironing-tool.

The oscillation of the head 25 is accomplished by means of a lever 44, pivoted at 45 to the upper cross-beam 12 and carrying at one end a segmental gear 46, which intermeshes with a corresponding gear 47, formed on the cross member 30 of the head, the opposite end of the lever 44 being connected with the pitman 36.

As a convenient means for connecting the pitman 36 with the arms 33 and 44, there is shown a block 48, with the lower end of which the pitman 36 is in threaded engagement. The upper end of the block 48 is bifurcated, the arm 33 entering its slot and being secured by means of a pivot-pin 49. (Shown in Fig. 4.) A threaded eyebolt 50 is pivoted at 51 within the slot of the block 48 above the point of attachment of the arm 33, the upper end of the eyebolt being in threaded engagement with a knuckle 52, pivotally attached to the lever 44 by a pin 52a. The threaded engagement of the pitman 36 with the block 48 and of the eyebolt 50 with the knuckle 52 admits of a suitable adjustment to bring the several parts of the mechanism into proper relation. The pivot-pin 49 is projected laterally beyond the block 48, as shown at 53, and carries a roller 54, running in a slot 55 in the side wall of the standard 10, this slot being slightly curved in order to communicate a longitudinal movement to the ironing-tool as it rocks.

The table having been raised into engagement with the ironing-tool, this movement effecting a sufficient compression of the spring 42 to provide the necessary pressure upon the work, the rocking action of the tool is effected by setting the shaft 38 in motion, and the head 25 is caused to oscillate in unison with the tool, thereby raising and lowering the abutment against which the upper end of the spring 42 is seated uniformly with the abutment carried by the tool itself, against which the lower end of the spring is seated, and thus maintaining a uniformity of pressure throughout the entire movement of the tool.

I claim as my invention—

1. In an ironing-machine, in combination, a rocking ironing-tool; an oscillating head; a sleeve pivotally attached to the head; a rod

pivots attached to the tool and slidable within the sleeve; an expansion-spring mounted upon the rod and reacting between abutments carried, respectively, by the head and by the ironing-tool; and means for rocking the head and the ironing-tool simultaneously.

2. In an ironing-machine, in combination, a rocking ironing-tool; an expansion-spring bearing on the back of the tool; an adjustable abutment against which the spring reacts; means for rocking the ironing-tool; and means for shifting the adjustable abutment simultaneously and correspondingly with the movement of the ironing-tool to maintain a uniform spring tension.

3. In an ironing-machine, in combination, a curved-faced ironing-tool; an arm projecting from the tool; an oscillatory head having a segmental rack; a lever having a segmental rack in mesh with the rack on the head; a reciprocating pitman connected with the arm of the ironing-tool and the lever; a sleeve pivotally attached to the head; a rod pivotally attached to the ironing-tool and slidable in the sleeve; and an expansion-spring reacting between the ironing-tool and the sleeve.

4. In an ironing-machine, in combination, a curved-faced ironing-tool; an arm projecting from the tool; an oscillatory head having a segmental rack; a lever having a segmental rack in mesh with the rack on the head; a reciprocating pitman connected with the arm of the ironing-tool and the lever and being adjustable with reference to one of such members; a sleeve pivotally attached to the head; a rod pivotally attached to the ironing-tool and slidable in the sleeve; and an expansion-spring reacting between the ironing-tool and the sleeve.

5. In an ironing-machine, in combination, a vertically-movable ironing-table; a suspended ironing-tool having a curved face and normally occupying a lower plane than the level of the table when the table is in its elevated position; an oscillatable head; a sleeve pivotally attached to the head; a rod pivoted to the ironing-tool and slidable through the sleeve; a head at the upper end of the rod for engaging the sleeve; an expansion-spring on the rod and reacting between the ironing-tool and the oscillatable head; and means for simultaneously and uniformly oscillating the head and rocking the ironing-tool.

WILLIAM E. ANDREE.
